UNITED STATES PATENT OFFICE.

JOHN E. PARKISON, OF SEATTLE, WASHINGTON, ASSIGNOR OF ONE-HALF TO ED H. PARKISON, OF ENCAMPMENT, WYOMING.

ABDOMINAL SUPPORT.

Application filed February 21, 1927. Serial No. 169,971.

This invention relates to body supports and particularly to supports for the abdomen.

The primary object of this invention is the provision of an improved and simplified form of support for this purpose.

A further object is the provision of a support which is comfortable to the wearer and which will remain in correct position at all times.

Another object is the provision of a support which will apply pressure at the point desired without squeezing the body in at the sides, or portions of the front not covered with pad.

Another object is the provision of a support which is adjustable in length within wide limits so that one given size will fit a number of different persons.

Another object is the provision of a support which has no exposed rigid portions to chafe or rip the wearing apparel of the user.

Another object is the provision of an improved pad construction. And yet another object is the provision of a support embodying the above features which will at the same time be inexpensive to manufacture and durable in use. Other objects and certain features of novelty residing in the invention will be apparent from the following description taken in connection with the accompanying drawings forming a part of this specification and in which:

Figure 1 is a front perspective view of the device;

Figure 2 is a central girdle section of the device with one of the belt clasps removed from its hook;

Figure 3 is a rear elevational view of the device;

Figure 4 is a vertical section taken substantially on the line 4—4 of Figure 3;

Figure 5 is a vertical section taken substantially on the line 5—5 of Figures 1 or 2; and

Figure 6 is a vertical section taken substantially on the line 6—6 of Figure 3.

Referring more particularly to the drawings, wherein like reference characters refer

to like parts throughout the several views, 10 generally denotes a pad carrying assembly and 11 generally denotes a belt assembly. Primarily then, the support may be said to comprise two units which may be readily assembled together upon the wearer or separated completely from each other.

The pad carrying unit 10 comprises a bow or splint 12, a pad 13, and a hook plate 14. The bow is made of a resilient but moderately stiff material such as spring steel, seasoned wood or the like. The bow has the general form of an incomplete ellipse comprising the front portion 12^a and the ends 12^b which ends may and preferably do extend beyond the major axis of the ellipse so as to provide means in the nature of arms or levers for canting the front portion 12^a of the bow for a purpose which will hereinafter appear. The width of the bow between its curved ends and the curvature of its front portion will, of course, depend upon the size and shape of the body for which the support is intended. Rotund bodies may require a bow having considerable curvature at the front while thin bodies may require a bow having little or no curvature along the front.

The pad 13 consists of a substantially stiff plate 13^a of metal, gutta-percha or the like, rigidly secured at the desired point along the bow 12 by screws or bolts 13^b. As clearly illustrated in Fig. 5, the bow member 12^a at the point where the plate 13^a is attached is made straight on the front side and inwardly inclined from top to bottom on the rear side to give an inward tilt to the bottom of the pad. This provides somewhat of a lift or support for the abdomen.

This plate may be covered if desired and for this purpose a soft pack 13^c may be secured to the plate by a fabric or chamois cover 13^d. The cover embraces one side of the pack and is secured to the edges of the plate 13^a in any suitable manner, as by stitches taken thru the cover and thru holes 13^e (Fig. 5) provided about the edges of the plate. For convenience in inserting fresh packing beneath the cover one edge may be left free of the edge of the plate

and have a flap 13^c secured thereto for detachably securing the cover to that edge of the plate. Preferably the flap is caught over a rounded edge of the plate (the lower edge Figs. 1 and 5) in order that it may be slipped on and off by virtue of a slight elasticity or give in the material of the cover or flap. When desired, of course, the entire pad or merely the stiff plate alone may be wrapped with an antiseptic fabric adapted to be changed frequently to keep the support in a clean and sanitary condition.

The hook plate 14 may be secured to the front of the bow 12 by rivets or bolts 14^a and is provided at either end with catches 14^b which may be made in the form of studs or hooks (as illustrated) or in any other convenient form, depending of course on the type of clasps provided on the belt unit for use in conjunction with the catches.

The belt unit 11 comprises essentially a band 16 and straps 17 secured thereto. The band 16 is made up of a central web or elastic section 16^a, intermediate sections 16^b on either side of the web section, and end sections 16^c. The end sections are reinforced and provided with pockets 16^d (as shown most clearly in Fig. 6) to accommodate the ends 12^b of the bow 12.

Each of the straps 17 is made of a substantial material such as ribbed webbing and is secured at its end to the band adjacent one edge of the central web section 16^a and at another point along its length to the end section 16^c adjacent its inner end but extends free of the intermediate section 16^b. A pair of auxiliary straps 17^a, 17^b are secured at and extend at an angle from the point where the strap 17 is secured to the end section 16^c to points respectively above and below the end of strap 17 where they also are secured to the edge of the section 16^a. Near the point where they are secured to the end sections 16^c the straps 17 are provided with loops 17^c carrying buckles 17^d.

Clasps 17^e adapted to be caught on hooks 14^b are provided with links 17^f of proper size to slip over the strap 17 in such manner that when the free end of the strap is passed thru the link and caught in the buckle 17^e the clasp will be held in the end of the loop thus formed. Since the strap is of considerable length and may be caught at any point along its length by the buckle, the clasp may be secured at any number of different adjusted positions to vary the effective length of the belt for different body sizes.

A strap 18 may be secured to one of the clasps 17^e to be brought over to the other clasp for covering the clasps and hooks when the support is assembled on the wearer.

The method of assembling the support on the body of the wearer will be readily understood from the foregoing description.

The belt band 16 is placed against the back of the body and the ends 12^b of the bow slipped into the pockets 16^d. The band is then pulled up over the bow until it is sufficiently tight, the pockets being of sufficient length to provide this adjustment. The straps 17 are threaded thru the links 17^f of the clasps 17^e and the buckles 17^d and fastened when the strap length is such as just to permit the clasps to engage the hooks. When the clasps have been hooked the strap 18 is brought over the clasps and hooks and fastened in the link of the clasp on the other side. This protects the clothing of the wearer from the metal parts. In daily use, after the support has once been adjusted to proper size, the belt is fastened and unfastened about the body at that end provided with strap 18, the other clasp being left fastened to keep the parts of the support together. The strap 18 serves as a handle for pulling up the end of the belt portion against the resistance offered by the expansion of the body.

From the above description it will be evident that this support has many advantages. One of these advantages resides in the tendency of the support always to maintain itself in correct position. This provides for the elimination of all auxiliary stay straps employed with the usual types of abdomen supports heretofore known or used. When the back of the belt of my support has a tendency to shift up due to some movement of the body likely to cause such shifting, the ends 12^b of the bow, which as stated extend at an angle to the bow and act as levers, will tend to move down to cant the front portion 12^a of the bow. Now since the plate 13^a is a rigid or substantially rigid member and rigidly secured to the bow, its lower edge will be pressed with increased pressure against the body of the wearer. The body of course tends to force the edge of the plate outwardly and will thereby resist and prevent any tendency of the brace to shift position. In other words, the pad does not follow the slippage of the back of the belt but resists such slippage. And on the other hand, the back of the belt being of considerable width and resting above the pelvic projections of the body will resist any tendency of the pad to slip up or down.

While one specific embodiment of this invention has been particularly described it will be understood that the invention is not thus limited but is susceptible of various changes and modifications in each and all of its parts and I do not therefore wish to be limited except by the prior art and the scope of the appended claims.

Having thus described the invention, what is claimed as new and desired to be secured by Letters Patent is:

1. In a body support in combination, a

substantially rigid bow member, a pad secured to said bow member, a flexible belt member, said belt member comprising a band and straps secured thereto adjacent the ends thereof, a pocket formed on each end of said band for removably and adjustably receiving the ends of the bow, a clasp adjustably secured on each strap, and means on said bow member for detachably securing said

10 clasps.

2. In a body support in combination, a bow front member having laterally extending curved ends, a belt member cooperating with said bow member, said belt member comprising a band and straps, said band including a relatively wide web section in the back, intermediate fabric sections on either side of said web section and tapered end sections having pockets to accommodate the 15 ends of the bow member, each of said straps comprising a single strip and angular branching end strips connected to the edges of the web section and the end sections but free of the intermediate sections, said single 20 strips extending beyond the ends of the band and means for adjustably securing the free ends of the straps to the front of said bow member.

25

In testimony whereof I hereunto affix my
30 signature.

JOHN E. PARKISON.
